3 SHEETS—SHEET 3.

UNITED STATES PATENT OFFICE.

WILLIAM H. HULSE, OF BROOKLYN, NEW YORK.

TABULATING DEVICE FOR TYPE-WRITERS.

933,840.

Specification of Letters Patent. Patented Sept. 14, 1909.

Application filed August 2, 1907. Serial No. 386,686.

To all whom it may concern:

Be it known that I, WILLIAM H. HULSE, a citizen of the United States, and a resident of Brooklyn, county of Kings, and State of New York, have invented certain new and useful Improvements in Tabulating Devices for Type-Writers; and I do herewith declare that the following is a full and clear description thereof.

10 My invention relates to tabulating devices for typewriters, the purpose of which is to free the carriage from its regular escapement mechanism and to arrest it at certain previously determined places on any line desired, and a prominent characteristic of 15 my improvements is that therein the two engaging stop members are fixed in position so far as movement relative to their supports in the direction of the carriage line movement is concerned, but the point or points of engagement of such members is or are adjusted at will.

The particular construction of the tabulating device is set forth in the following specification and shown in the accompanying drawings which illustrate in detail only the tabulator itself, omitting all parts of the typewriting machine not necessary to the explanation.

30 Figure 1 is a rear view of a typewriting machine, showing the location of the tabulator; Fig. 2 is a plan view thereof; Fig. 3 is a side elevation of Fig. 1, showing the carriage and part of the tabulator in cross-section; Fig. 4 is a rear view of the tabulator frame; Fig. 5 is a detail view of the rack bar of the tabulator; Fig. 6 is a detail view of the double pawl fastened on the carriage; Fig. 7 is a detail view of the finger lever 35 located near the keyboard of the machine for setting the tabulator, and Fig. 8 is a modified form of the tabulator frame shown in Fig. 4.

In Fig. 3, 1 is the machine frame of the typewriter (shown in dotted lines) in which the carriage 2 may be disposed in any well-known manner, for instance, rolling on bars 3 between rails 4 which are part of the machine frame and may be operated by any well-known propelling mechanism used in these machines (not shown in the drawings). The step by step forward motion of carriage 2 may be also controlled in any well-known manner, for instance, by pinion 5 engaging 50 in rack bar 6 suitably fastened to the car-

riage, the pinion being controlled through shafting 7 by the escapement device 8, Fig. 1. Rack bar 6 is pivotally mounted within the frame of carriage 2 by pivot pins 9 and may be held in engagement with pinion 5 either 60 by its own weight or by any other suitable means, for instance, a spring, so that in operating hand-lever 10 (shown in dotted lines) rack bar 6 may be tilted upward by the operator and the carriage thus freed 65 from the control of the escapement device.

Underneath rack bar 6 is disposed lever 11 pivotally mounted on a lug 12 of the machine frame 1 by pivot screw 13 so that its upper end is bearing against rack bar 6, its 70 lower end being provided with a roller 14. Near roller 14 is arranged the shaft 15 journaled slidingly on both ends in machine frame 1 and having near roller 14 cone 16 fixed to it by set screw 17. Shaft 15 is held 75 longitudinally in the position shown in Fig. 3 by means of spring 18 bearing on one end against lug 19 which is fixed to frame 1 and on the other end against collar 20 fixed on shaft 15. It will be seen, in Figs. 1 and 3, 80 that if shaft 15 is shifted longitudinally to the left, roller 14 of lever 11 will roll up the inclined surface of cone 16, thereby lifting with its other end rack bar 6 from the engagement with pinion 5 and thus freeing the 85 carriage from the control of the escapement mechanism and enable it to either run freely or under such control as may be provided until stopped by the tabulating device to be described later on. Shaft 15 is provided at 90 its right hand end, which protrudes through frame 1 of the machine near the keyboard, with a finger lever 26 having a knob 27 by means of which an axial and an angular motion may be imparted to shaft 15. Finger 95 lever 26 is further provided at its upper end with segment 28, shown in front view as seen from the keyboard in Fig. 7. The upper edge of segment 28 is provided with notches 29, corresponding in number with 100 the number of digits which may be written by the machine before the decimal point, in this instance eight notches being provided. These notches are adapted to engage stop finger 30, secured to machine frame 1, when 105 shaft 15 is shifted in axial direction to the left by pressing knob 27 (Fig. 3). The outer end of stop finger 30 is cut away at its under side to allow segment 28 to play freely within the limits set by the projections 110 45

on segment 28, which at the extreme positions of lever 26 engage the outer end of lever 30. On the upper part of the rear of the machine frame 1 are provided two brackets 31, one on each side of the machine, in which a swinging frame 32 is pivotally mounted to have movement in axial direction besides its angular movement, which is obtained by having the pivots 33 (shown 10 in detail in Fig. 4) axially extended the length which frame 32 is to be shifted. On one end of frame 32 is fastened an arm 34, which extends downwardly and is pivoted at its free end to the upwardly extending 15 arm 35 of shaft 15 (Figs. 1 and 3) so that by shifting shaft 15 to the rear of the machine and into the position shown in dotted lines in Fig. 3, frame 32 will be tilted into the dotted position shown in Fig. 3, and 20 and furthermore, if shaft 15 is angularly operated by means of lever 26, frame 32 may be axially shifted, owing to the long pivots 33.

On carriage 2 is fastened on a suitable 25 place, bracket 36, detail view of which is shown in Fig. 6. On this bracket is pivoted double pawl 37, held in the position shown in this figure by means of spring 38 suitably fastened at the upper end of bracket 36. 30 Underneath pawl 37 is mounted on frame 1, tabulator rack bar 39 (as shown in detail in Fig. 5) so that if pawl 37 is operated on one end by suitable means, it will engage with the other end in the teeth of rack bar 39, thus locking carriage 2. The pawl 37 and rack bar 39 form the two engaging stop members of my improvement, and are so supported that the pawl while moving with the carriage has no movement longitudinally 40 thereof, and the rack bar is held from longitudinal movement on the machine frame.

To the upper side of tabulator frame 32 is fastened a scale 40, divided according to the number of letters or numerals which 45 may be written on one line and provided with a row of holes, one hole on each demarcation of the scale, in which holes plugs 41 may be inserted. These plugs are of suitable length to protrude into the path of the 50 double pawl 37 when frame 32 is tilted into the dotted position (Fig. 3). If now during the writing operation the carriage is moving from the left to the right (Fig. 1), one end of pawl 37, as shown in this figure, 55 will strike a plug of frame 32, in case the latter is in tilted position, so that the other end 42 of pawl 37 will be tilted downwardly and engage in one of the teeth of tabulator rack bar 39 and bring the carriage to a stop. 60 The mechanism is adjusted in regard to time so that during the axial movement of shaft 15, frame 32 with its plugs 41 will be tilted first into the path of pawl 37 and thereafter lever 11 will be operated by cone 65 16 to release the carriage rack bar from the

pinion 5. If upon release of knob 27 shaft 15 is returned to its normal position by means of spring 18, carriage rack bar 6 will be first brought into engagement with its pinion 5, whereafter tabulator frame 32 returns from its dotted position into its normal position.

It will be obvious to anyone skilled in the art that in the practical construction of the device pivot point 33 of frame 32 should be 75 sufficiently close to the vertical line through pawl 37 and rack bar 39 (Fig. 3) that pin 41 at the time in engagement with pawl 37 will not have an undue upward motion when frame 32 is tilted back into its normal position.

The manner of operation of the tabulating device is as follows: After the desired space between the columns has been set by 80 inserting pins or plugs 41 at the proper places on scale 40 the device is ready for column writing. On moving finger lever 26 angularly so that finger 30 will engage the notch denoted by "0", the carriage will stop by the device described above at the column 90 point which is, regarding its position on the line, equal with the decimal point of the numbers to be written. On releasing finger lever 26, carriage 2 will be brought again under the control of the escapement mechanism, and 95 any number of decimals may be written after the decimal point. If now, for instance, the number "325" is to be written in the next column of the same line, finger lever 28 is angularly moved until notch 3 (which 100 corresponds with three digits before the decimal point) registers with finger 30, whereafter this lever is pressed inwardly into the dotted position shown in Fig. 3, which motion releases the carriage from the escapement, as described above, and causes same to run in the writing direction until its pawl 37 strikes the operating plug of the next column, which causes pawl 37 to stop the carriage, in the manner above described, 110 at the proper place that is to say, three digits before the decimal point as required by the number "325" to be written. It will be seen that thus the carriage will be held in this position so long as the operator presses 115 the finger lever:

While I have shown in the drawings a particular form of my tabulating device, I do not wish to limit myself to this one form, since the same purpose may be obtained in various other ways, the fundamental idea of my invention being that after the carriage has been released from the escapement mechanism and is free to move, it is stopped whenever an operating pin or plug comes 125 into action, by a device on the carriage operated by these pins. Furthermore, instead of providing the tabulator frame 32 with a detachable scale 40, which allows the using 130 of a number of scales, on each of which may

be set columns of different widths, I may also have the scale on the longitudinal bar of the frame, as shown in Fig. 8.

I claim:

5. 1. In a tabulator, the combination of a carriage, permanently positioned carriage stopping means, means on the carriage adapted to engage said permanently positioned means to stop the carriage at any desired place on the line during the writing, and adjustable means disposed and operated independently of the carriage for causing said engaging means to operate by the forward movement of the carriage.

15. 2. In a tabulator, the combination of a carriage, permanently positioned carriage stopping means extending along the path of the carriage, means on the carriage adapted to engage said permanently positioned means to stop said carriage at any desired place on the line during the writing process and adjustable means disposed and operated independently of the carriage for causing said engaging means to operate by the forward movement of the carriage.

25. 3. In a tabulator, the combination of a carriage, a tabulator rack bar, means on the carriage adapted to engage said rack bar to stop said carriage at any desired place on the line during the writing process, and adjustable means disposed and operated independently of the carriage for causing said engaging means to operate by the forward movement of the carriage.

35. 4. In a tabulator, the combination of a carriage, permanently positioned carriage stopping means, a pawl on said carriage adapted to engage said permanently positioned means to stop said carriage at any desired place on the line during the writing process, and adjustable means disposed and operated independently of the carriage for causing said pawl to operate by the movement of said carriage.

45. 5. In a tabulator, the combination of a carriage, a tabulator rack bar, a pawl on said carriage adapted to engage said rack bar to stop said carriage at any desired place on the line during the writing process, and adjustable means disposed and operated independently of the carriage for causing said pawl to operate by the movement of the carriage.

55. 6. In a tabulator, the combination of a carriage, a tabulator rack bar disposed in parallel to the path of said carriage, a pawl disposed on the carriage to engage said rack bar to stop the carriage at any desired place on the line during the writing process, and 60 a tabulator stop bar having adjustable operating pins, said stop bar pivoted to swing said stops into the path of said pawl, causing said pawl to engage said tabulator rack bar to stop the carriage, and means for operating said tabulator stop bar.

7. In a tabulator for typewriting machines, the combination of a carriage adapted to run transversely to the machine and means normally controlling the movement of said carriage, permanently positioned carriage stopping means, and means on the carriage adapted to engage said permanently positioned means to stop said carriage at any desired place on the line, adjustable means adapted to operate said engaging means, and hand operated means for freeing the carriage from its normal controlling means and setting said adjusting means into operative position to stop the carriage at the place desired.

15. 8. In a tabulator for typewriting machines, the combination of a carriage adapted to run transversely to the machine, and means normally controlling the movement of said carriage, a tabulator rack bar, means on the carriage adapted to engage said tabulator rack bar to stop said carriage at any desired place on the line, adjustable means adapted to operate said engaging means, and hand operated means adapted to set said adjustable means into operative position and free the carriage from its normal controlling means in sequence to stop the carriage at the place desired.

25. 9. In a tabulator for typewriting machines, the combination of a carriage adapted to run transversely to the machine, and means normally controlling the movement of said carriage, permanently positioned carriage stopping means, a pawl on said carriage adapted to engage said stopping means to stop said carriage at any desired place on the line, adjustable means adapted to operate said pawl, and hand operated means adapted to set said adjustable means into operative position and to free the carriage from its normal controlling means in sequence to stop the carriage at the place desired.

35. 10. In a tabulator for typewriting machines, the combination of a carriage adapted to run transversely to the machine, and means normally controlling the movement of said carriage, a tabulator rack bar, a pawl on said carriage adapted to engage said rack bar to stop said carriage at any desired place on the line, adjustable means adapted to operate said pawl, and hand operated means adapted to set said adjustable means into operative position and to free the carriage from its normal controlling means in sequence to stop the carriage at the place desired.

45. 11. In a tabulator for typewriting machines, the combination of a carriage adapted to run transversely to the machine and means normally controlling the movement of said carriage, a tabulator rack bar, a pawl on said carriage adapted to engage said rack bar to stop said carriage at any desired place on the line, a tabulator stop bar adapted to

operate said engaging means, and hand-operated means disposed to set said stop bar into operative position and to free the carriage from its normal controlling means in sequence to stop the carriage at the place desired.

12. In a tabulator for typewriting machines, the combination of a carriage adapted to run transversely to the machine, and means normally controlling the movement of said carriage, a tabulator rack bar disposed in parallel to the path of said carriage, a pawl disposed on the carriage adapted to engage said rack bar to stop said carriage at any desired place on the line, and a tabulator stop bar having adjustable tabulating stops, said stop bar pivoted to swing said tabulator stops into the path of said pawl, causing same to engage in said rack bar, and hand-operated means disposed to tilt said stop bar into operative position and to free the carriage from its normal controlling means in sequence.

13. In a tabulator for typewriting machines, the combination of a carriage adapted to run transversely to the machine, and means normally controlling the movement of said carriage, a tabulator rack bar disposed in parallel to the path of said carriage, a pawl disposed on the carriage adapted to engage said rack bar to stop the carriage at any desired place on the line, and a tabulator stop bar having adjustable tabulator stops, said bar pivoted to have angular motion and motion in axial direction and adapted to swing said tabulator stops into the path of said pawl, causing same to engage in said tabulator rack bar, and hand-operated means disposed to shift said stop bar in axial direction as desired and to tilt the same into operative position and to free the carriage from its normal controlling means in sequence.

14. In a tabulator for typewriting machines, the combination of the fixed frame of the machine, a carriage moving thereon, a rack bar having teeth corresponding in their distance from each other with the letter spaces on one line, and a tilting pawl, one of said elements on each of said members, pins or operating members for said pawl, the pawl having a portion adapted to engage any of said pins to move the pawl in engagement with said rack bar, the space intervals between two consecutive steps of the carriage caused by said pins being equal to one or more than one letter space at will.

15. In a tabulator for typewriting ma-

chines, the combination of the fixed frame of the machine, a carriage moving thereon, a rack bar having teeth corresponding in their distance from each other with the letter spaces on one line, and a tilting pawl, one of said elements on each of said members, pins or operating members for said pawl, and means for adjustably positioning said pins relatively to each other, the pawl having a portion adapted to engage any of said pins to move the pawl in engagement with said rack bar, the space intervals between two consecutive steps of the carriage caused by said pins being equal to one or more than one letter space at will.

16. In a tabulator for typewriting machines, the combination of the fixed frame of the machine, a carriage moving thereon, a rack bar having teeth corresponding in their distance from each other with the letter spaces on one line, and a tilting pawl, one of said elements on each of said members, pins or operating members for said pawl, the pawl having a portion adapted to engage any of said pins to move the pawl in engagement with said rack bar, the space intervals between two consecutive steps of the carriage caused by said pins being equal to one or more than one letter space at will, and indexed hand operated means for varying the longitudinal position of any of said pins relatively to the fixed pawl of the escapement mechanism of the typewriting machine.

17. In a tabulator for typewriting machines, the combination of the fixed frame of the machine, a carriage moving thereon, a rack bar having teeth corresponding in their distance from each other with the letter spaces on one line, and a tilting pawl, one of said elements on each of said members, pins or operating members for said pawl, and means for adjustably positioning said pins relatively to each other, the pawl having a portion adapted to engage any of said pins to move the pawl in engagement with said rack bar, the space intervals between two consecutive steps of the carriage caused by said pins being equal to one or more than one letter space at will, and indexed hand operated means for varying the longitudinal position of any of said pins relatively to the fixed pawl of the escapement mechanism of the typewriting machine.
